UNITED STATES PATENT OFFICE.

R GUY COWAN, OF LAKewood, OHIO.

DESIGN FOR A FLOWER HOLDER.

Application filed March 27, 1926. Serial No. 17,075. Term of patent 7 years.

To all whom it may concern:

Be it known that I, R GUY COWAN, a citizen of the United States, residing at 1499 Cohasset Avenue, Lakewood, in the county of Cuyahoga and State of Ohio, have invented a new, original, and ornamental Design for a Flower Holder, of which the following is a specification, reference being had to the accompanying drawing, forming part hereof.

The figure is a perspective view of a flower holder showing my new design.

I claim:

The ornamental design for a flower holder, as shown.

R GUY COWAN.
